ADJUSTABLE INFRARED ENERGY SENSOR UNIT

Danilo V. Missio, 60 Rockmont Drive,
Belmont, Mass. 02178

Filed Mar. 2, 1972, Ser. No. 231,442

Term of patent 14 years

Int. Cl. D13—99

U.S. Cl. D26—1 F

Fig. 1.

Fig. 2.

Fig. 3.

Fig. 4.

Fig. 5.

Fig. 6.

Fig. 7.

FIG. 1 is a front perspective view of an adjustable infrared energy sensor unit with the cover thereon showing my new design;

FIG. 2 is a front perspective view of FIG. 1 with the cover removed;

FIG. 3 is a rear perspective view of FIG. 2;

FIG. 4 is a front elevational view thereof;

FIG. 5 is a right side elevational view thereof, the left side being substantially a mirror image thereto;

FIG. 6 is a bottom plan view thereof; and

FIG. 7 is a rear elevational view thereof.

I claim:

The ornamental design for an adjustable infrared energy sensor unit, as shown and described.
